UNITED STATES PATENT OFFICE

MOSES S. DIAMOND, OF NEW YORK, N. Y., ASSIGNOR TO SAMUEL DIAMOND, OF NEW YORK, N. Y.

HUMIDOR

Application filed January 24, 1929. Serial No. 334,801.

This invention relates generally to smokers' appliances, and the improvements are directed to a novel and unique form of humidor adapted to maintain the contained smoking material in a condition whereby the excellence of said material is retained for the fullest enjoyment of the user.

In view of the inherent absorptive characteristic of the tobacco leaf, either in the form of smoking tobacco, or cigars, it is essential that stored quantities thereof be protected from changing climatic conditions, and to this end many forms of containers have been devised whereby the circulation of air therein may be reduced to a minimum. Several of the forms now presented to the consuming public employ the well-known gasketed joint, but in most instances the constant contacting of the edges of a closure member tends to destroy the usefulness of this type of joint and as a result the gasket is pierced and the attending circulation of air to the contained smoking material ultimately renders the same unfit for use.

Therefore, the salient objective of the present invention is the production of a humidor wherein smoking material, in the form of cigars, or the like, may be temporarily stored and maintained at all times in perfect smoking condition.

Another object is to provide a novel form of frame member, adapted for association with the container portion of a humidor, said member being arranged adjacent the top thereof and provided with a bridging or elastic member which cooperates with a closure to effect the tight sealing of said humidor.

Still another object of the invention is the provision of a frame member formed to define a channel extending continuously around the top open portion of a container, said member being uniquely bent to provide an anchorage for an elastic element bridging the open portion of said channel.

A still further object is to provide a frame member of the above-mentioned character with a plurality of bent portions which serve to imprison the edge portions of an elastic element and which are further adapted to

cooperate with the latter, to assure an air-tight connection, when said element is stretched into the channel portion by the action of a flange carried by a closure member.

A still further object of the invention is to provide a humidor which may be made in various sizes to accommodate a suitable amount of smoking material, in the form of cigars, or the like, said humidor being maintained in an air-tight condition to prevent the circulation of air to the contained material.

A final, but nevertheless, important object of the invention is to construct the same on sturdy lines and of few and simple parts, whereby it may operate efficiently for long periods and sell at a reasonable figure.

With the above objects in view and any others which may suggest themselves from the specification and claims to follows, a better understanding of the invention may be gained by reference to the accompanying drawings, in which—

Fig. 1 is a vertical longitudinal sectional view of the humidor embodying my invention, a portion of the closure member being also shown.

Fig. 2 is a plan view of the container or body portion of said humidor to illustrate the continuous channel formed by the frame member, the closure portion of said humidor being removed.

Fig. 3 is a sectional view, somewhat enlarged, of a corner of said humidor, the closure member being elevated in this view.

Fig. 4 is a sectional view somewhat similar to Fig. 3, but illustrating the closure member closed and its flange stretching the elastic element and distending the same into the channel portion of the frame member to effect the tight sealing of said humidor, and

Fig. 5 is an inverted plan view of the closure member, slightly reduced, to illustrate the flange thereof.

Referring now more in particular to the accompanying drawings, wherein like characters of reference denote similar parts throughout the several views, let 5 denote generally my improved humidor, which com-

prises essentially a container or body portion 6, of suitable proportions, to which is hingedly mounted a closure member 7, as indicated at 8. Into said body portion 6 will be placed the smoking material, such as 5 cigars, or the like, and in order that said material may be maintained in perfect smoking condition it is proposed to provide means whereby air will be excluded from said container when the closure member is closed.

To this end I have provided a frame member, generally denoted by the numeral 9, which conforms to the shape of said humidor, whether the same be square, rectangular or round, said frame member being positioned adjacent the top of said container and spaced from the sides thereof by spacing member 10, or the like. In the example of 15 the invention, shown in the drawings, the upper face portion of said frame member 9 is flush with the top edges of said container 6. The opening 11 provides access means for the placement or removal of the smoking material in said humidor.

Upon inspection of Fig. 3 of the drawings, which shows a typical transverse section of 25 said frame member 9, it will be observed that the same is preferably formed from a single piece of material, which is bent to the form indicated, its medial portion presenting a downwardly directed channel 12 having a web portion 13, the upper portion of each of the sides 14 merging with the reversely bent portion 15 and 16, while the extremities of 30 said frame member are each bent to substantial rectangular form in cross section, as indicated at 17, the end portions are then bent upon themselves, as shown at 18, to present a downwardly disposed rounded edge portion 35 19. As will presently appear this particular form of bending produces a frame member admirably adapted to imprison an elastic element 20 and to maintain the same in a position to be distended or stretched by a depending flange 21 of said closure 7.

It has been premised that said elastic element 20 is adapted to be distended into said channel 12, and in order that same element 20 may be maintained in proper position, I propose to anchor each of the edge portions 50 thereof within the frame member, and as shown in Fig. 3, the rounded edge portions 19 each serve to imprison the same within the bent portions 16, while the medial portion 55 of said elastic member 20 bridges the upper portion of said channel 12 and it is this portion which is distended or stretched into said channel while the edge portions remain firmly secured as pointed out hereinbefore. When 60 the closure is opened said elastic element 20 assumes the position shown in Fig. 3 and this condition may be referred to as normal since the cooperation of said elastic element and 65 channel 12, become apparent only when the

closure member is in the position shown in Fig. 4.

Upon inspection of said Fig. 4 it will be noted that the closure is now sealing the opening 11 and that the flange 21 thereof has distended the medial portion of said elastic element 20 into said channel 12, and the humidor is now in an air-tight condition, as is quite obvious. It will be further observed that the bottom or contacting edge of said flange 21 is 70 rounded to prevent abrasion of said elastic element, and further the provision of the rounded reverse bends 15—16 precludes the cutting or otherwise destruction of said element. Obviously, as the said elastic element 75 is stretched into said channel the inner portions of said element intimately contact the bends 15 and effects an air-tight contact, and the further tight contact of the rounded edge of said flange 21 with said element positively 80 precludes the entrance of air or moisture into the humidor when the closure is in the position indicated in Fig. 4.

From the foregoing it is apparent that my improved humidor includes a sealing element 85 which is capable of being distended as desired and since its edge portions are anchored between rounded surfaces and further in view of the contact of the stretched portion of said element with rounded surfaces throughout, 90 the chances of tearing or puncturing are exceedingly remote.

Obviously various slight changes might be made in the general form and arrangement of the parts described without departing from 95 the invention, and hence I do not limit myself to the precise details set forth, but consider myself at liberty to make such changes and alterations as fairly fall within the spirit and scope of the appended claims.

I claim:

1. In a humidor including a hinged closure having a depending flange, a frame member positioned in the top of said humidor and formed to present a continuous channel extending into said humidor and an elastic strip normally bridging said channel and having its opposite edge portions secured to said frame member and adapted to be stretched into said channel by the flange of said closure.

2. In a humidor including a hinged closure having a depending flange, a frame member positioned in the top portion of said humidor, said member being formed to define a downwardly extending channel and having its ends bent downwardly and arranged adjacent the sides of said channel and an elastic strip normally bridging said channel and having its edge portions clamped by the aforesaid bent ends, the medial portion of said strip being adapted to be distended into said channel by said flange when said closure is closed.

3. In a humidor including a hinged closure having a depending flange presenting a rounded bottom edge, a frame member posi-

tioned in the top portion of said humidor, said member having its medial portion bent to present a downwardly directed channel, the upper portion of each of the sides of the channels being formed to define reversely bent portions, the extremities of said member being bent to substantial rectangular form, in cross-section, and presenting a downwardly directed end portion, and an elastic strip normally bridging said channel and having its edge portions clamped between the aforesaid bent ends and one of the reversely bent portions, the medial portion of said strip being adapted to be stretched and distended into said channel by said flange when said closure is closed.

In testimony whereof I affix my signature.
MOSES S. DIAMOND.
